ELECTROMAGNETIC RESET VALVE

William A. Ray, Glendale, Calif., assignor to
General Controls Co., a corporation

Application June 5, 1943, Serial No. 489,801

12 Claims. (Cl. 137—144)

1

This invention relates to a reset valve for fluid fuels.

Such reset valves are used in fuel supply systems to ensure against flow of fuel to the burner unless a pilot flame is lit. A valve of this character is usually arranged to be maintained open by an electromagnet energized by a thermocouple, or a thermopile in the pilot flame. Then the main cock may be turned on and off, as desired, the pilot flame serving to ignite the fuel passing through the main burner whenever the cock is opened.

If the pilot flame should be extinguished, the safety valve closes. To re-establish the fuel supply, the safety valve may be manually reset to open position and held in the open position until the pilot flame is ignited. If the flame for any reason fails to ignite, release of the reset valve causes the valve to close again; and a resetting operation must be again attempted.

A safety valve of this general character is described in an application filed in the name of William A. Ray, on February 4, 1941, Serial No. 377,274, entitled "Reset valve and control therefor."

It is an object of this invention to provide such a valve of compact and simplified construction and having an improved mode of operation.

It is another object of this invention to make it possible to control the passage of fuel to the pilot burner during the resetting operation, in a convenient and simple manner.

It is another object of this invention to provide a reset valve including a main valve, and a supplemental valve for independently controlling a pilot burner, and having a single actuator which is optionally operable for operating the main valve or the supplemental valve.

It is a still further object of this invention to provide a reset valve including a main valve and a safety valve, and so arranged that operation of the main valve acts directly to actuate the safety valve.

It is a still further object of this invention to provide a reset valve arranged to give an indication when the main or manually operable valve is closed.

This invention possesses many other advantages, and has other objects which may be made more easily apparent from a consideration of one embodiment of the invention. For this purpose there is shown a form in the drawings accompanying and forming part of the present specification. The form will now be described in detail, illustrating the general principles of the

2

invention; but it is to be understood that this detailed description is not to be taken in a limiting sense, since the scope of this invention is best defined by the appended claims.

5 In the drawings:

Figure 1 is a longitudinal section through a valve incorporating the invention;

Figs. 2, 3, and 4 are sections as seen on correspondingly numbered planes of Fig. 1;

10 Fig. 5 is a view similar to Fig. 1, but showing the valve in a different operating position;

Fig. 6 is a fragmentary section as seen on plane 6—6 of Fig. 1; and

15 Fig. 7 is a diagram indicating the various operating positions of the main valve closure.

This valve is of the type for controlling the fluid fuel supply to a burner which is intermittently operated, a constantly lighted pilot burner being provided for igniting the main burner after periods of inactivity.

20 The valve structure comprises a main valve 3 which is manually operable for optionally controlling the supply of fuel to a main burner (not shown). Obviously it is important to provide

25 means whereby, upon extinguishment of the main burner and of the pilot burner, the supply of fuel to these burners is interrupted. Further, means must be provided for preventing re-establishment of the supply to the main burner until the pilot

30 burner has been relighted. For this purpose, a safety valve 1 is provided controlling the passage of fuel through the valve and adapted to be retained in open position by an electromagnet 2 energized in response to electricity generated by

35 the heat of the pilot burner flame in a well known manner, as by a thermocouple (not shown). Upon the extinguishment of the pilot burner for any reason, coil 2 is de-energized, permitting valve 1 to close, and stopping all fuel

40 supply to the burners. To avoid a dangerous condition when the valve 1 is opened, the means for opening valve 1 are so arranged that main valve 3 must be closed before the valve 1 can be opened. Further, before valve 3 can be opened,

45 without permitting valve 1 to close, the pilot burner must be lighted to energize magnet 2 to retain valve 1 in open position. To permit a fuel supply to the pilot burner when valve 1 is open and before valve 3 is opened, a by-pass 4 is provided in valve 3.

To facilitate proper lighting of the pilot burner and to make it possible to prevent supply of fuel to the pilot burner until the operator is ready, a supplemental valve 5 is provided in by-pass 4, which is automatically 50 closed when the main valve 3 closes, but which

may be opened before valve 3 is opened. However, means are provided so that, when the main valve 3 is open, supplemental valve 5 is maintained open. A common actuating means 6 is provided for valves 3 and 5, being arranged for movement in one plane to open and close valve 3 and for movement in a direction out of this plane to open valve 5.

The valve structure comprises an elongated body 10 having axially aligned threaded openings 11 and 12 at its opposite ends for connection to suitable conduits and forming, respectively, the inlet and outlet. Between the inlet and outlet openings 11 and 12 is a transverse opening 13, closed by a detachable cover 14. There is also a boss 15 extending transversely of body 10 and forming a seat 16 for a tapered rotary plug 17, and a web wall 18, the boss 15, plug 17, and wall 18 serving to interrupt communication between the inlet 11 and outlet 12. To establish communication between the inlet and the outlet, plug 17 has an axial port 19 adapted to connect with inlet 11 and intersected by a radial port 20 adapted to connect with outlet 12 through port 21 in the boss 13. Rotation of plug 15 in seat 16 serves to place ports 20 and 21 into or out of registry as desired.

Safety valve 1 includes a valve member 23 in the form of a disc of magnetic material adapted to co-operate with a valve seat 24 formed on the end of valve plug 17. A light compression spring 25 urges disc 23 to seat 24. When member 23 is on seat 24, communication between inlet 11 and port 19 is interrupted; hence, no fluid can pass from inlet 11 to outlet 12 regardless of the registry of ports 20 and 21. A cam surface comprising a pair of cams 26 is formed on the upper end of plug 17, and means forming a co-operating cam surface 27 is secured to valve disc 23, so that rotation of plug 17 serves to raise disc 23 from seat 24 against the force of spring 25 and into contact with the face 28 of the electromagnet 2 mounted in cover 14. This magnet 2, upon appropriate energization, retains valve disc 23 in open position. Electromagnet 2 is supported within cap 14 by a single screw 29, and is provided with leads 30 and binding posts 31 for connection with a suitable source of electric current, such as a thermocouple.

Since the fluid passing through the valve carries a certain amount of sticky material, dirt, etc., likely to be deposited within the valve, and, particularly since the force exerted by magnet 2 is small, it is desirable to protect face 28 of the magnet, as well as the co-operating face of disc 23, from the fluid. Otherwise, a deposit of such material on these faces would seriously reduce the holding power of the magnet 2, or possibly cause the disc to stick in open position. For this purpose a short metallic bellows or Sylphon 33, surrounding face 28, is secured to the lower surface of electromagnet 2 and to disc 23.

It is, of course, necessary to prevent disc 23 and cam means 27 from rotating in order that rotation of plug 17 and cam means 26 will be effective to raise disc 23. For this purpose an inverted cup 34 is secured within cap 14, as by being clamped between the upper end of magnet 2 and the under surface of cap 14, serving to enclose magnet 2 and spring 25. Cup 34 has its lower edge serrated to provide teeth 35, which engage arcuate slots 36 formed on the periphery of disc 23.

The energization of electromagnet 2 by the thermocouple is purposely such that the magnet

is incapable of attracting disc 23 from its dropped position.

It is, accordingly, desirable that appropriate rotation of plug 17 will cause the cams 26 and 27 to bring valve disc 23 directly into contact with face 28. To allow for manufacturing tolerances, as well as to guard against urging disc 23 against face 28 with such force as to damage the parts, a member 38, having a plurality of resilient fingers 39, is interposed between cam means 27 and disc 23. As clearly shown in Fig. 1, cam means 27 is secured to disc 23 by a screw 40 having a flat sided portion 41, the cam means 27 being axially slidable on portion 41 and urged downwardly therewith by spring fingers 39. Thus, when cam means 27 is moved upwardly, as by cam means 26, this upward movement is imparted to disc 23 through fingers 39; and, upon disc 23 contacting face 28, further upward movement of cam means 27 merely flexes fingers 39.

The by-pass port 4 for supplying the pilot burner comprises a circumferential groove 44 on plug 17, extending partly around the periphery thereof, and communicating with port 19 through a radial port 45. The boss 15 of body 10 has an extension forming a chamber 46 for accommodating the supplemental valve 5 which may comprise a ball 47 urged as by spring 48 toward a seat 49, formed on a plug 50 threaded into the lower end of chamber 46. That portion of chamber 46 above seat 49 is open to groove 44 and hence to ports 45 and 19 through port 51, while that portion of chamber 46 below seat 49 comprising bore 52 of plug 50 communicates with tube 53 which leads to the pilot burner (not shown) via ports 54, 55, and 56. Seating of ball 47 interrupts communication between the interior of plug 17 and tube 53. A push rod 57 extends through plug 50, upward movement of rod 57 serving to unseat ball 47 against the force of spring 48.

The actuating means 6 for operating the valves will now be described, attention being directed to Figs. 1, 4, and 5. A circular disc or actuator 60, with a knurled periphery adapted to be conveniently gripped by the fingers, is slidably mounted on the flat sided portion 41 of a downward extension 62 of plug 17, being retained thereon by a nut and washer 63 and 64. A compression spring 65 urges disc 60 downwardly against washer 64, the upper end of spring 65 seating against a washer 66 having an upturned retaining edge 67. To prevent any upward movement of plug 17 and consequent unseating thereof with respect to seat 16, incident to manipulation of actuator 60, a retaining nut 68 is threaded on stem 62 and maintains washer 66 in contact with the lower surface of body 10.

Appropriate rotation of the knob or actuator 60 will rotate plug 17 to place ports 20 and 21 into or out of registry, as well as to cause cam 26 to unseat valve disc 23. Further, actuator 60 has a raised portion or holding surface 70 which engages push rod 57, maintaining supplemental valve 5 open, this surface 70 having a sloping portion 74 which acts as a cam on rod 57 to cause valve 5 to open or close in response to rotation of the actuator 60.

The angular relationship existing between the cams and ports is best described in connection with the mode of operation of the valve. In this connection attention is called to Figs. 4 and 7, the latter being a diagrammatic showing of plug 17 and actuator 60. In both Figs. 4 and 7, the parts are shown as in the positions they occupy when the main valve 3 is fully open, as in Fig. 1.

In Fig. 1 the safety valve 1 is shown as closed, as after accidental extinguishment of the pilot burner, or upon initiating operation of the burner; hence no fuel can flow to either the pilot burner or the main burner.

In a reset valve of this character, the closing of the main or manually operable valve 3 serves to open the automatic or safety valve 1. Since the main valve 3 must be fully closed before the safety valve 1 commences to open, the operating connection between the valves must include a lost motion provision. In the present instance, this lost motion is provided by suitable angular spacing between the co-operating cam surfaces 26 and 27, as illustrated in Fig. 3.

Stop means are provided for appropriately limiting angular movement of actuator 60; this may comprise lugs 71 and 72 on the actuator 60 for engaging respectively with a boss 73 on body 10. In the fully open position of Figs. 1, 4, and 7, lug 71 contacts boss 73. Movement of actuator 60 and plug 17 counterclockwise from this position will cause ports 20 and 21 to pass successively out of registry and then to close until, after 90° of movement, the main valve 3 may be regarded as effectively closed. This is indicated in Fig. 7 by lines 100, 101, and 102, which may be considered as successively reaching dart 103 in response to counterclockwise movement of actuator 60 and plug 17. After the amount of movement represented by the angle between dart 103 and line 102, cam surfaces 26 and 27 are still out of contact, hence valve 1 is still closed; further, the supplemental valve 5 is still open, due to rod 57 still being on holding surface 70. However, a small additional counterclockwise movement will bring the edge of cam surface 74 under push rod 57, allowing valve 5 to begin to close, further movement causing valve 5 to close completely. This can be visualized in Fig. 7 as the successive arrival of lines 104 and 105 at dart 103. All valves are now closed. Further counterclockwise movement of plug 17 brings cam surfaces 26 on the plug into engagement with the co-operating surfaces 27 on the valve disc 23 of safety valve 1, additional counterclockwise movement of plug 17 causing valve 1 to be fully opened and brought into contact with face 28 of magnet 2, and can be visualized by the successive arrival of lines 106 and 107 at dart 103.

It is now necessary to cause magnet 2 to be energized, as otherwise, upon returning plug 17 to open position, valve member 23 will immediately return to its seat 24 and prevent any fluid passing to valve 3. For this purpose, the pilot burner must be ignited and kept burning for a brief period until the thermocouple heated thereby generates sufficient current to energize magnet 2.

Supplemental valve 5 must therefore be opened. This is accomplished by pressing actuator 60 toward body 10 and against the force of spring 65, causing push rod 57 to lift ball 47 from its seat 49. After an interval sufficient to allow the thermocouple to become active, actuator 60 is returned clockwise at least far enough to bring the end of rod 57 onto the holding surface 70 while still elevated; and then the actuator is brought to its original position with lug 71 engaging boss 73 and ports 20 and 21 in registry. Ample space is provided in chamber 46 about ball 47 to accommodate the ball 47 when actuator 60 is urged upwardly and push rod 57 is on the holding surface 70. Hence, it is not material when the actuator 60 is allowed to return to its lower position in response to spring 65, so long as

as it is maintained elevated long enough to ensure that valve 5 is held open.

It is to be noted that the provision of valve 5 for controlling the fuel supply to the pilot burner 5 has important advantages. Thus, no fuel flows to the pilot burner until the operator is ready to ignite it, and all possibility of an accumulation of unignited fuel is avoided. Further, this valve is opened by a short easy movement distinct from that necessary to open the main valve.

In addition to the safety features of the valve, it is intended for use as a control. Thus, by turning the plug counterclockwise from the position of Figs. 1, 4, and 7, the flow of fuel to the main burner may be restricted or stopped entirely, that is, from the position indicated by line 102 to that indicated by line 103 of Fig. 7. Conversely, by turning the plug clockwise from the closed position, the flow of fuel may be initiated and regulated to any desired proportion of a full flow. For this purpose, it is, of course, essential that the pilot burner not be extinguished accidentally. Referring to Fig. 7, it will be noted that the angular movement of the actuator 60 necessary to close the valve 5 which controls fuel to the pilot burner is substantially greater than that required to close the main valve 3. Accordingly, such normal operation is easily accomplished; however, to facilitate it, means are provided for exerting a momentary restraint, as well as giving audible warning when the plug 17 reaches a fully closed position and before the pilot valve 5 closes.

For this purpose a detent 77 is slidably mounted in a bore 78 in boss 73, being continually urged against the actuator 60 by a spring 79. A depression 80 is provided in the surface of actuator 60 for receiving the detent 77, and is so positioned angularly with respect thereto as to be engaged by detent 77 when plug 17 is in closed position, and when the plug is being turned from open position before holding surface 70 has moved from under push rod 57 and allowed valve 5 to close. It will be apparent, when detent 77 is in engagement with depression 80, a restraint will be placed on the movement of actuator 60, requiring additional force to overcome it and move the actuator farther to pilot extinguishing position. Further, an audible click will result when the detent 77 drops into depression 80. Accordingly, accidental movement of the actuator 60 past closing position for main valve 3, with resulting inconvenience due to extinguishing the pilot, will be avoided. The actuator may be readily turned beyond this position when necessary until stop 72 engages boss 73 and the safety valve 1 is opened.

The inventor claims:

1. In a reset valve mechanism for fluid fuels, a main valve structure, a safety valve structure, each of said structures having a movable valve closure, means for causing the safety valve closure to move to open position in response to movement of the main valve closure to a closed position, means controlled by said safety valve closure for supplying fuel to a pilot burner, and supplemental means for causing said supplying means to be closed in response to the closing of the main valve, said supplemental means including an optionally operable member for temporarily holding said supplementary means in fuel supplying position.

2. In a reset valve mechanism for fluid fuels, a main valve structure, a safety valve structure, each of said structures having a movable valve closure, means for causing the safety valve closure

to move to open position in response to movement of the main valve closure to a closed position, means controlled by said safety valve closure for supplying fuel to a pilot burner, a supplemental valve controlling said supplying means, means constantly urging said supplemental valve toward closed position, and means connected to the main valve closure for causing said supplemental valve to be maintained in open position upon arrival of the main valve closure to an open position, and means for independently moving said means that is connected to the main valve closure when the main valve is closed, for opening the said supplemental valve.

3. In a reset valve mechanism for fluid fuels, a main plug valve having a rotary closure member, as well as a valve body member in which the closure member is seated, said closure member having a main fuel passageway adapted to be placed into and out of communication with a passage in the body, a safety valve closure cooperating with one of said members to interrupt the passage of fuel, cam means carried by the rotary closure member for urging said safety valve closure to open position after the rotary closure member reaches a valve closing position, a manually operable member for rotating said rotary closure member, a valve for controlling the passage of fuel to a pilot burner, means urging said pilot burner valve toward closed position, and means carried by said manually operable means for opening said controlling valve by movement of said manually operable means in a direction axial of the rotary closure member.

4. In a valve structure for fluid fuels, a main valve structure for controlling passage of fuel to a main burner, a supplemental valve for controlling passage of fuel to a pilot burner, actuating means for operating said main valve to open and to close, means causing said supplemental valve to close in response to closing of the main valve, said actuating means being optionally operable to open said supplemental valve independently of the main valve.

5. In a valve structure for fluid fuels, a main valve structure including a rotary plug for controlling passage of fuel to a main burner, a safety valve structure including a closure for controlling passage of fuel to the main burner and to a pilot burner, a supplemental valve for controlling passage of fuel to the pilot burner, and an actuator connected to said plug for operating the plug and the safety valve closure, and movable axially of the plug for operating said supplemental valve to supply fuel to the pilot burner.

6. In a valve structure for fluid fuels, a main valve structure including a rotary plug for controlling passage of fuel to a main burner, a supplemental valve for controlling passage of fuel to a pilot burner, means urging said supplemental valve to close, and an actuator connected to said plug for operating the plug and movable axially thereof, said actuator having a holding surface maintaining said supplemental valve open while the main valve is open, and a depressed surface for permitting the supplemental valve to close when the main valve is closed, axial movement of the actuator serving to open the supplemental valve.

7. In a reset valve mechanism for fluid fuels, a main valve structure for controlling passage of fuel to a main burner, a supplemental valve for controlling passage of fuel to a pilot burner, a safety valve structure for controlling passage of fuel to said main valve and to said supplemental

valve, actuating means for operating said main valve to open and to close, means opening said safety valve in response to movement of the main valve to closed position, means closing said supplemental valve in response to closing of the main valve, said actuating means being optionally operable to open said supplemental valve independently of the main valve, and means for retaining said safety valve in open position.

10 8. In a valve structure, a rotary plug, a valve body providing a seat in which said plug is accommodated, said plug being operable to control the passage of fluid by way of the plug, and having for that purpose a passageway opening in one end of the plug, means adjacent the end of said passageway forming a safety valve seat around the axis of the plug, a closure adapted to co-operate with said seat for controlling passage of fluid through said passageway and movable toward and away from said seat, interengaging cam means carried respectively by said plug and said closure and acting generally along the axis of the plug for moving said closure to open position in response to rotation of the plug in one direction, means for retaining said closure in open position, and means for operating said plug.

15 9. In a valve structure, a rotary plug, a valve body providing a ported seat in which said plug is accommodated, said plug being operable to control the passage of fluid by way of the plug and having for that purpose a port adapted to connect with the port in said seat upon rotation of the plug, as well as a passageway communicating with said port and opening in one end of the plug, means adjacent the end of said passageway forming a safety valve seat around the axis of the plug, a closure adapted to co-operate with said seat for controlling passage of fluid through said passageway and movable toward and away from said seat, cam means on said plug for moving said closure in response to rotation of the plug disconnecting said ports, said cam means acting on the closure generally along the axis of the plug, means for retaining said closure in open position, and means for rotating the plug.

20 10. In a valve structure, a rotary plug, a valve body providing a seat in which said plug is accommodated, said plug having a port to control the passage of fluid by way of the plug, means forming a safety valve seat around the axis of the plug, a closure adapted to co-operate with said seat for controlling the passage of fluid by way of the plug and movable toward and away from said seat, and means forming a cam surface on the plug acting directly on said closure generally along the axis of the plug for operating said closure in response to rotation of the plug.

25 11. In a valve structure, a rotary plug, a valve body providing a seat in which said plug is accommodated, said plug having a port to control the passage of fluid by way of the plug, said plug having for that purpose a passageway opening in one end of the plug, means adjacent the end of said passageway forming a safety valve seat, said seat surrounding said passageway, a safety valve closure adapted to co-operate with said seat for controlling the passage of fluid through said passageway and movable toward and away from said seat, and means forming a cam surface carried by the plug for moving said closure in response to rotation of the plug, said cam means acting on the closure generally along the axis of the plug.

30 12. In a valve structure, a rotary plug, a valve

body providing a seat in which said plug is accommodated, said plug serving to control the passage of fluid through the valve, means forming a safety valve seat around the axis of the plug, a closure co-operating with said seat for controlling the passage of fluid by way of the plug and movable toward and away from said seat, and a crown cam on an end of the plug for operating said closure in response to rotation of the plug, said cam acting on the closure generally along the axis of the plug.
